DELOS M. PALMER, OF TOLEDO, OHIO, ASSIGNOR TO WESTINGHOUSE ELECTRIC & MANUFACTURING COMPANY, A CORPORATION OF PENNSYLVANIA

TEMPERATURE-INDICATING DEVICE

Application filed July 27, 1927. Serial No. 208,722.

My invention relates to temperature-responsive devices and particularly to devices in which temperature indications may be obtained in response to changes in the ohmic resistance of an electric conductor.

An object of my invention is to provide a temperature-indicating device that shall be simple in construction, easily manufactured and efficient in its operation.

10 Another object of my invention is to provide a temperature-indicating device for dynamo-electric machines that shall depend for its operation upon the change in the ohmic resistance of a magnetic-field-producing winding.

15 A further object of my invention is to provide a temperature-indicating device for current-traversed bodies to be protected from overheating that shall be operable in response to the current traversing the bodies, its operation being independent of auxiliary sources of electromotive force.

20 A further object of my invention is to provide a temperature-indicating device for dynamo-electric machines that shall indicate the temperature of a field-producing winding by the change in the ohmic resistance thereof, and electromagnetic means for rendering the indicating device non-responsive to current variations or surges which may take place in the machine.

25 In practicing my invention, I provide a temperature-indicating device for dynamo-electric machines that comprises, in general, a plurality of resistors so connected in circuit with a field-producing winding of the machine that a Wheatstone bridge circuit is formed. An electro-responsive instrument may be connected to the galvanometer points 30 of the bridge in order that the thermal condition of the winding may be ascertained by the change in the resistance of the field-producing winding. Means are provided, also, for neutralizing the effect of current surges 35 in the machine upon the indications of the instrument.

40 For a fuller understanding of my invention, reference may be had to the following description taken in conjunction with the accompanying drawings, wherein,

Fig. 1 is a schematic illustration of circuits and apparatus embodying my invention, and

Fig. 2 is a similar view of a modification of the circuits and apparatus illustrated in Fig. 1.

In Fig. 1 of the drawings, a dynamo-electric machine, such as a direct-current series motor, is illustrated that is provided with an armature 11 and a series field-producing 50 winding 12 having portions 13 and 14 and a short field tap 15 therefor.

Connected in parallel-circuit relation with the portion 13 of the field winding 12 and a substantially constant-resistance shunt 16 is 55 a resistor 17, resistance of which does not change with temperature. One end of the resistor 17 may be connected, by a conductor 18, to one terminal member 19 of the shunt 16. The other end of the resistor 17 may be 60 connected to the short field tap 15 by means of a conductor 20 and a movable connector 21.

In order that the temperature of the field-producing winding may be determined, an electro-responsive instrument 22 is connected 65 between a point 23 on the resistor 17 and another terminal 24 on the shunt 16. The instrument may be either a direct-current ammeter or any other instrument suitable for my present purpose.

70 The instrument 22 is provided with a scale 25 and a pointer 26. If desired, one half of the scale 25 may be colored red or any other suitable color, and the other half may be white or some other suitable color that differs from that of the first half.

75 Having thus described the field winding, the shunt 16, the resistor 17 and the connection of the instrument 22 thereto, it is readily seen that the resistor 17, the shunt 16 and the portion 13 of the field winding are connected in the form of a Wheatstone-bridge circuit. By properly adjusting the connector 21, the Wheatstone bridge may be caused to be substantially in balance when the temperature of the portion 13 of the field-producing winding has reached a predetermined 80 value.

85 The portion of the resistor 17 between the point 23 and the adjustable connector 21 may 90

95

be so adjusted that, when the portion 13 of the field winding 12 has reached a temperature of a predetermined value, say 105° C., the drop in potential between the point 23 and the connector 21 is substantially equal to the voltage drop across the portion 13 of the field winding 12. When this condition obtains, the movable pointer 26 is preferably in the position shown in Fig. 1 of the drawings. If the temperature of the field winding 10 increases to a temperature above 105° C., the pointer 26 is caused to move into the region of the red or colored band, for example, the right-hand portion of the scale, and, if the temperature falls below this value, the pointer deflects into the left-hand portion of the scale 25.

In order that sudden variations or current surges, which may take place in the armature 11, may not affect the indication of the instrument 22, a transformer 27 is provided. The transformer 27 comprises a primary winding 28 that is connected in series between the armature 11 and the shunt 16, and a secondary winding 29 that is connected between the point 24 on the shunt 16 and the instrument 22. With these circuit connections in mind, it is obvious that any potential induced in the winding 28 is balanced by a substantially equal and opposite potential in the winding 29. Therefore, no electromotive force will be available, as a result of current surges in the motor circuit, to affect the indications of the instrument 22. It is desirable that magnetic characteristic of the transformer be substantially the same as that of the field-producing winding in order that the transformer may operate properly.

The winding 29 of the transformer 27 may be provided with a bridging member 30 for short-circuiting as many of the turns of the winding 29 as desired, depending upon the number of turns required in the circuit of the instrument 22 to counterbalance the effect of current surges in the motor.

The armature 11 and the field winding 12 may be energized from a suitable source of electromotive force represented by conductors 31 and 32.

In Fig. 2 of the drawings, the transformer 27 and the portion 14 of the field winding 12 have been omitted. In other respects, the operation of the system and apparatus there illustrated is substantially the same as that in Fig. 1.

It is to be understood that the resistance between the point 23 and the variable connector 21 may be adjusted to any value, depending upon the exact temperature to be indicated by the instrument 22; that is, if it is desired that the instrument 22 shall indicate exactly the temperature of the field winding 12, when the value of the temperature is substantially 100° C., or any other desired reference temperature, the resistance between the point 23 and

the variable connector 21 is so adjusted that, when the winding has been heated to 100° C. temperature, the pointer 26 of the instrument 22 will indicate this temperature. If the temperature rises above or falls below the above 70 temperature, the pointer 26 will indicate, not necessarily the exact temperature, but that the temperature of the winding 12 is either above or below the reference temperature, which reference temperature may be the maximum safe temperature to which the field winding shall be subjected. 75

The characteristics of the temperature-indicating device are such that, when a current of a predetermined value traverses the field winding 12, the instrument 22 will indicate substantially the actual temperature of the field winding over its entire scale. The maximum or limiting safe temperature, however, will always be indicated correctly, regardless 80 of the value of current traversing the field-producing winding. 85

While I have illustrated a series motor in Figs. 1 and 2 of the drawings, it is to be understood that the method of measuring the 90 temperature, as hereinbefore set forth, may be applied to other motors as well. For instance, the temperature of the commutating-pole winding of a shunt motor may be ascertained substantially in the manner set forth herein and, by this method, the safe temperature to which the motor may be heated may be obtained, for, in this type of motor, the commutating-pole winding carries a portion of the current traversing the armature. Obviously, the invention may be applied to other dynamo-electric machines and current-carrying 95 devices. 100

Various modifications may be made in the device embodying my invention without departing from the spirit and scope thereof. I desire, therefore, that only such limitations shall be placed thereon as are imposed by the prior art and the appended claims.

I claim as my invention:

1. In combination with an electrical field winding, a temperature-indicating device for said winding comprising said winding and a plurality of resistors connected to form a Wheatstone-bridge circuit, an electro-responsive instrument connected to the galvanometer points of the bridge and mutual inductive means coupling the circuits of said instrument and said winding, whereby said instrument is rendered substantially non-responsive to sudden variations in current in the winding. 115

2. In combination with an electrical winding, a temperature-indicating device for said winding comprising said winding and a plurality of resistor elements connected to form a Wheatstone-bridge circuit, an electro-responsive instrument connected to the galvanometer points of said bridge and a transformer having one winding thereof connected 125 130

in series-circuit relation to said bridge circuit and the other winding thereof connected in circuit with said instrument.

3. In combination with an electrical winding, a temperature-indicating device for said winding, said device comprising said winding and a plurality of resistor elements connected to form a Wheatstone-bridge circuit, an electro-responsive instrument connected to the galvanometer points of said bridge, and means for rendering said instrument substantially non-responsive to sudden variations of electric current in said winding.

In testimony whereof, I have hereunto subscribed my name this 20th day of July, 1927.

DELOS M. PALMER.
